Office Action dated Nov. 8, 2011 for U.S. Appl. No. 29/360,841, filed Apr. 30, 2010.

Primary Examiner — Paula Greene

(74) *Attorney, Agent, or Firm* — Alston & Bird LLP

(57) **CLAIM**

The ornamental design for a stackable container, as shown and described.

DESCRIPTION

FIG. 1 is a perspective view of a stackable container showing our new design;

FIG. 2 is an elevation front view of the stackable container shown in FIG. 1;

FIG. 3 is an elevation side view of the stackable container shown in FIG. 1, the opposite side being a mirror image thereof;

FIG. 4 is an elevation rear view of the stackable container shown in FIG. 1;

FIG. 5 is a plan top view of the stackable container shown in FIG. 1; and,

FIG. 6 is a plan bottom view of the stackable container shown in FIG. 1.
